CLAIM

The ornamental design for a boot for an inline skate, as shown.

DESCRIPTION

FIG. 1 is a front elevational view of a boot for an inline skate showing our new design;

FIG. 2 is a rear elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The broken line showing of line wheels is for illustrative purposes only and forms no part of the claim.
